(57) **CLAIM**

The ornamental design for a material having an edge shape, as shown and described.

DESCRIPTION

FIG. 1 is a perspective view of a material having an edge shape, showing our new design;

FIG. 2 is a cross-sectional perspective view of the material having an edge shape of FIG. 1, taken along lines 2-2 in FIG. 1;

FIG. 3 is a top plan view of the material having an edge shape of FIG. 1;

FIG. 4 is a right side elevation view of the material having an edge shape of FIG. 1; and,

FIG. 5 is a left side elevation view of the material having an edge shape of FIG. 1.

The broken lines in FIGS. 1-7 illustrate portions of the material having an edge shape that form no part of the claimed design.
